US0D1079044S

(12) **United States Design Patent** (10) **Patent No.:** **US D1,079,044 S**
(45) **Date of Patent:** **** Jun. 10, 2025**

(54) **PERCUSSION MASSAGER**

(71) Applicant: **MerchSource, LLC**, Irvine, CA (US)

(72) Inventors: **Mark Filipek**, Mission Viejo, CA (US);
Denny SzuPao Liao, Tustin, CA (US)

(73) Assignee: **MerchSource, LLC**, Irvine, CA (US)

(**) Term: **15 Years**

(21) Appl. No.: **29/933,408**

(22) Filed: **Mar. 19, 2024**

Related U.S. Application Data

(60) Continuation-in-part of application No. 29/888,170, filed on Mar. 28, 2023, which is a division of application No. 29/806,040, filed on Aug. 31, 2021, now Pat. No. Des. 987,844.

CLAIM

The ornamental design for a percussion massager, as shown and described.

DESCRIPTION

FIG. 1 is a top, perspective view of the front and left side of a percussion massager of the present design.

FIG. 2 is a bottom, perspective view of the rear and right side of the percussion massager of FIG. 1.

FIG. 3 is a side elevation view of the left side of the percussion massager of FIG. 1.

FIG. 4 is a side elevation view of the right side of the percussion massager of FIG. 1.

FIG. 5 is a front elevation view of the percussion massager of FIG. 1.

FIG. 6 is a rear elevation view of the percussion massager of FIG. 1.

FIG. 7 is a top plan view of the percussion massager of FIG. 1; and,

FIG. 8 is a bottom plan view of the percussion massager of FIG. 1.

The dash-dot broken lines shown in the drawings are for the purpose of showing boundary lines, which form no part of the claimed design.

1 Claim, 6 Drawing Sheets
